UNITED STATES PATENT OFFICE.

ALEXANDER MARCY AND HERMAN BYRON MARCY, OF CLINTON, ONTARIO,
CANADA.

MOUSE AND DUST PROOF ATTACHMENT FOR ORGANS.

SPECIFICATION forming part of Letters Patent No. 393,773, dated December 4, 1888.

Application filed November 18, 1887. Serial No. 255,543. (No model.)

To all whom it may concern:

Be it known that we, ALEXANDER MARCY and HERMAN BYRON MARCY, citizens of the United States, residing in Clinton, in the county of Huron, in the Province of Ontario, Canada, have jointly invented a new and useful Mouse and Dust Proof Attachment for Organs and Harmoniums, of which the following is a specification.

10 Our invention consists of a mouse and dust proof attachment for organs and harmoniums. It may be made of wood or metal, and can be fastened to the inside end of the pedals or to the upper or inside end of the 15 pedal-frames, so as to close against the ease inside and close the opening over the pedals or between the pedals and the ease; or it may be fastened inside the case so the pedals will close against it; or part of it may be fastened to the inside end of the pedals or pedal-frames and part of it may be fastened inside of the ease, so that the parts of the attachment will come together or pass each other and close the opening over the pedals and 25 exclude mice and dust, as illustrated in the accompanying drawings, in which—

Figure 1 is an elevation of the mouse and dust proof attachment. Fig. 2 is a plan of the mouse and dust proof attachment. A is the toe-piece for the inside end of the pedals or for the inside end of the pedal-frames; or it may be fastened inside the case for the 30 pedals to close against; or part of it may be fastened to the case and part of it to the 35 pedals, so as to come together.

Fig. 3 is a section of the mouse and dust proof attachment.

Figs. 1, 2, and 3 are one-half actual size.

Fig. 4 is a section of the mouse and dust proof attachment, showing it when made in connection with or cast on the upper or inside end, and is a part of the pedal-frames. Fig. 4 is three-quarters of actual size.

Fig. 5 is a perspective view of the mouse and dust proof attachment when fastened to

the pedal or pedal-frame or the ease also when part of it is fastened to the pedal or pedal-frame and part to the case.

Similar letters refer to similar parts throughout the several views.

In the drawings, II is the pedal, made to rest the feet on. An organ or harmonium case has an opening in front to receive the pedals, as illustrated in Fig. 4. The opening in the ease E extends from the pedal II to the line 55 under E about one inch high over the pedals. This opening is necessary, so as to give the feet room to rest on the pedals; but it allows mice to go inside the case.

Our mouse and dust proof attachment closes 60 the opening, and, being inside the case, is not in the way of the feet, as shown and described.

Fig. 4 is a section showing the mouse and dust proof attachment made or cast with and being a part of a well-known metal pedal-frame, M. The mouse and dust proof attachment is the upper or inside end of the metal pedal-frame M, as shown in Fig. 4. The toe-piece A, Fig. 1, extends the entire length of the upper or inside end of the pedal-frame and 70 pedal, and is high enough to close up against the ease E. The toe-piece A protects the pedal-strap O and gives the proper length of the pedal-strap O, so the pedals will be even.

What we claim as our joint invention, and 75 desire to secure by Letters Patent of the United States, is—

The combination, in a mouse and dust proof attachment, of the toe-piece A, the end or side pieces, B, the metal pedal-frame M, the 80 pedal II, the ease E, the block K, and the rubber face L, as shown and described, for the purposes set forth.

Signed this 24th day of October, 1887.

ALEXANDER MARCY.
HERMAN BYRON MARCY.

In presence of—

S. DOAN,
H. B. PROUDFOOT.
